UNITED STATES PATENT OFFICE.

BENJAMIN F. WADE, OF PALMETTO, FLORIDA.

PLUG FOR ELECTRICAL INSTALLATION.

Application filed August 27, 1920. Serial No. 406,327.

To all whom it may concern:

Be it known that I, BENJAMIN FRANKLIN WADE, a citizen of the United States, and a resident of Palmetto, in the county of 5 Manatee and State of Florida, have invented certain new and useful Improvements in Plugs for Electrical Installation, of which the following is a specification.

My invention is an improvement in plugs 10 for electrical installation, and has for its object to provide a plug which may be inserted and withdrawn from the socket without the necessity for turning the plug with respect to the socket, and wherein the electrical connections will be insured by the inserting of the plug.

A further object of the invention is to provide a plug of the character specified having a handle of such length that the plug 20 may be easily inserted into sockets provided with shades.

In the drawings:

Figure 1 is a longitudinal section through the plug;

25 Figure 2 is a side view looking at right angles to Figure 1;

Figure 3 is an enlarged longitudinal section of the engaging end of the plug;

30 Figure 4 is a perspective view of the insulating block of another form of plug;

Figure 5 is an end view looking at the outer end of the plug;

Figure 6 is a similar view looking at the inner end;

35 Figure 7 is a vertical section through the modified form of plug;

Figure 8 is a horizontal section at about the center of the plug;

40 Figure 9 is a perspective view of one of the push buttons;

Figure 10 is a horizontal section on the line of the push buttons.

In the embodiment of the invention shown in Figures 1 and 2, the plug is shown in 45 connection with a light socket 1 of usual construction, having the internal metallic shell 2 threaded to receive the plug. The plug comprises a block 3 of insulating material, as, for instance, porcelain, to which 50 is connected a substantially U-shaped plate, consisting of a body 4 arranged transversely of one end of the block and arms 5 extending on opposite sides of the block in spaced relation.

55 These arms, near their connection with the body, are grooved, as shown, to provide

threads for engaging the threaded metallic shell 2 and a handle is connected with the arms 5, the said arms being extended beyond the opposite end of the plug from the 60 body, as shown. This handle consists of similar sections 6 of insulating material, as, for instance, porcelain, and each handle section 6 is rigidly connected to the adjacent arm 5.

65 At the ends remote from the U-shaped plate the sections of the handle are loosely connected by a transverse bolt or rivet 7, whose heads are countersunk in recesses 8 in the outer faces of the handle sections. 70 Thus while the handle sections may move toward each other at their outer ends they cannot move away from each other beyond limits prescribed by the bolt or rivet. As shown in Figure 1 these handle sections are 75 curved transversely, and the conducting wires 9 from the plug 3 pass between the handle members.

The body 4 of the plate 4—5 is held in place in a transverse groove in the block 3, 80 by means of a flange 10 on an externally threaded socket or casing 11 which is held in a recess in the upper end of the block. This socket or casing is threaded into the recess in the block, and the flange 10 engages over an insulating washer 12 which is arranged between the flange and the body 85 4 of the plate 4—5, and it will be noticed, referring to Figure 3, that the body 4 of the plate has an opening through which the 90 socket or casing 11 extends, so that the socket is insulated from the body of the plate.

95 A conducting bar 13 is connected at its upper end to the plate 4, the said bar passing through an eccentric opening in the plug, and one of the conducting wires 9 is connected with the lower end of this bar by means of a screw 14, the bar having a head or flange 15 at its lower end. The 100 lower end of the plug 3 is recessed, as shown, to receive this head and screw, and to receive a conducting plate 16 with which the other wire of the pair 9 may be connected by means of a set screw 17. This plate 16 105 is integral with a conducting rod 18 which extends upwardly through an axial opening in the plug and is connected with the lower end of the socket by means of a washer 19 which fits into the lower end of the 110 socket.

A headed pin 20 is arranged at the upper

end of the socket, the head being within the socket and the pin extending out of the socket, and this pin is normally pressed away from the lower end of the socket by 5 means of a coil spring 21 arranged within the socket between the head of the pin and the washer 19. This pin 20 is intended to engage one of the contact members of the socket, to make the electrical connection, the 10 other connection being made through the metallic shell 2 and the plate 4—5. The opposite faces of the block 3 near its lower end are recessed, as shown in Figure 1, to receive coil springs 22 which are arranged 15 between the bottoms of the recesses and the arms 5 of the plate 4—5 and act normally to press said arms outwardly.

In the operation of this construction, when it is desired to withdraw the plug 20 from the socket, with the parts in the position of Figure 1, the handle sections 6 are merely pressed together at their free ends. This movement compresses the springs 22 and permits the handle and plug to be withdrawn 25 from the socket.

Figures 5 to 10 show the invention without the handle, being adapted to a plug for ordinary use. With this arrangement, the plug 23 which corresponds to the plug 3 of 30 Figure 1 has connected therewith a plate 24 corresponding to the plate 4—5 of Figure 1.

The arms of the plate 24 extend only to the lower end of the block 23, that is, to the end remote from the body of the plate 24. 35 Here coil springs 25 are arranged between the said arms and the block, it being noticed from an inspection of Figure 4 that the block is grooved longitudinally at its opposite sides, as shown at 26, to permit the 40 movements of the arms. The springs 25 seat at their inner ends in recesses 27 in the grooves and they engage at their outer ends the arms, normally acting to press said arms outward.

45 The insulating collar 28, which is detachably connected with the lower end of the block and which fits outside of the arms,

has oppositely arranged radial openings through which are movable the bodies 29 of push buttons, the heads 30 of the buttons 50 being outside the collar. The body of each of these buttons is longitudinally slotted, as shown at 31, and a pin 32 which extends transversely of the openings through which the buttons move engages the slot 31 of the 55 adjacent button, thus limiting the movement of the button with respect to the collar.

The buttons at their inner ends engage the arms of the plate 24, and it will be obvious 60 that by pressing the buttons inward the arms of the plate 24 will be moved toward each other, to release them from the threads of the socket. The conducting wires 33 are connected with a central contact bar 34, 65 and with an eccentric bar 38 in the same manner as they are connected in Figure 3, the spring arrangement shown in Figure 3 being also used in the present instance.

As indicated in Figure 8, the upper end 70 of the rod 34 is connected with a socket 36 corresponding to the socket 11 of Figure 3, and the coil spring 37 is arranged within the socket, the upper end of the spring bearing against the headed pin 38 corresponding 75 to the pin 20 of Figure 3, while the lower end engages the lower end of the socket.

I claim:

An attachment plug comprising a block 80 of insulating material, a substantially U-shaped contact having a body portion arranged at one end of the block and arms extending along the block, a socket carried by the block and having a flange for securing the body portion of the U-shaped contact to the block, an insulating washer between the flange and the body portion, a spring projected contact pin carried by the socket, an axial conductor rod electrically 85 connected with the socket and contact pin, and an eccentric conductor bar electrically 90 connected with the U-shaped contact.

BENJAMIN F. WADE.
